PLATING DEVICE FOR KNITTING MACHINES

Application filed March 2, 1931. Serial No. 519,586.

This invention relates to improvements in knitting machines, and it consists of the constructions, combinations and arrangements herein described and claimed.

5 An object of the invention is to provide a plating device for use in conjunction with circular hosiery knitting machines, the structural characteristics of the device and its combination with the machine being such 10 as to successfully plate the heels and toes of circular knit hosiery so that these parts are similar in appearance to the leg and instep of the stocking, but have the advantage of a practically invisible reinforcement at a reasonably low cost.

A further object of the invention is to establish a proper setting of the yarn carrier in reference to the mouthpiece especially for the counter-clockwise motion of the needle cylinder, so as to insure an avoidance of twisting the threads during this particular phase of the reciprocation of the needle cylinder while knitting heels and toes.

Other objects and advantages will appear 25 in the following specification, reference being had to the accompanying drawings in which

Figure 1 is a plan view of a fragment of a circular hosiery knitting machine particularly illustrating the improved mouthpiece and yarn carrier, illustrating the separation of the threads during counter-clockwise motions.

Figure 2 is a detail front elevation of the 35 principal parts shown in Figure 1.

Figure 3 is a plan view of the mouthpiece.

Figure 4 is a front elevation thereof.

Figure 5 is a plan view similar to Figure 1, illustrating the change in position of the threads and the maintenance of separation thereof upon reversal of the machine for clockwise rotation.

Figure 6 is a detail front elevation of the 45 structure in Figure 5.

Figure 7 is a horizontal section taken substantially on the line 7—7 of Figure 1, the yarn carrier especially being shown in elevation.

50 Figure 8 is a perspective view of the improved yarn carrier.

The instant disclosure of the invention is in connection with a circular knitting machine such as used for knitting seamless hosiery and the like, but this is not to be regarded as a limitation of the use of the invention because it can be used equally well with similar types of machines adapted for producing what is known as split foot type goods.

In knitting the high class hosiery of modern demands the necessity of using fine and high-priced materials has followed as a natural result. It is obviously highly desirable to preserve the fine appearance of the leg and instep in the generally hidden heel and toe of the stocking, yet to incorporate the reinforcing material in the heels and toes at a lesser cost.

The heel and toe are desirably reinforced in order to withstand the extra wear imposed on these parts, and while plating, or two-thread knitting as it is sometimes called, is known in circular knitting machines, yet as far as known no circular knitting machine has been adapted to plating heels and toes during the characteristic reciprocations of the needle cylinder when knitting heels and toes for the fundamental reason that no adequate means has been devised for keeping the threads properly separated when shifting from one angled position to the other.

As is commonly known, in knitting a piece of plated goods one thread shows on the face of the goods while the other is concealed. In the drawings the thread 1 is the face thread which is exposed on the outer surface of the 85 stocking, including the heel and toe, while 2 is the thread which is concealed in the heel and toe, serving to reinforce these parts.

A smooth appearance of the fabric where the heel and toe join the adjacent parts of the stocking is insured only by avoiding a twisting of the threads 1, 2 upon the reversal of the machine from rotary to reciprocatory knitting. This is generally hard to do, and especially so when the plating operation is 90 carried out during reciprocatory knitting, because then the likelihood of the threads contacting with each other, and as a result becoming twisted, is much increased.

This introduces the invention which has 100

as its primary purpose the separation of the threads 1, 2 in such a way that they cannot twist around each other upon reversal of the machine, and the mode by which this purpose is accomplished is as follows:—A yarn carrier 3 (Fig. 8) is located in a substantially central or medial position (Figs. 1 and 5) in respect to the passageway 4 (Fig. 4) of a mouthpiece 5, in so far as its horizontal dimension is concerned.

The description of the location of the yarn carrier 3 as being substantially central is made advisedly. It must be understood that some variation in position must be permissible in practice. It is of utmost importance to so set the yarn carrier that it will assume a perfect plating position on the counter-clockwise motion of the needle cylinder. This may require the location of the yarn carrier to one or the other side, but for all practical purposes the location may be regarded as medial respecting the passageway of the mouthpiece, considering the horizontal dimension of the latter.

This yarn carrier is deeply notched at 6 (Fig. 8) at a point near the extremity 7, the proportions of the notch and resulting head 8 being approximately equal as regards length. The head 8 has a horizontal eye or outlet 9 which opens at the extremity 7 and communicates with the notch 6 for the face yarn 1. Since this yarn is threaded through the eye 9 from behind it follows that the notch 6 must be sufficiently large to provide room.

Incidentally the notch 6 spaces the horizontal eye 9 from a vertical eye 10 in the body of the carrier 3. This eye guides the thread 2. This separation of the eyes 9, 10 places the backing thread of yarn 2 in back of the thread of face yarn 1. The eye 10 communicates with a relief 3 $\frac{1}{2}$ on the nether side of the yarn carrier 3, this relief providing the necessary room for the backing thread 2 (Fig. 7) in passing across the bottom of the mouthpiece either to one side or the other.

The bottom of the mouthpiece 5 with which the yarn carrier 3 coacts is decidedly angled toward the right on its front wall portion or outlet and delivery edge as at 11 (Fig. 3). The right end of the edge 11 becomes one wall of a channel 12 which is completed by a separator 13. This separator is nothing more than a prong or point stationed on the right side of the mouthpiece 5 and directed toward the left side, its purpose being to keep the yarn 2 separated from the yarn 1 (Fig. 5) when the knitting machine makes its clockwise turn.

On the side of the passageway 4 opposite to the channel 12 the wall of the mouthpiece has a pronounced undercut 14 (Figs. 3 and 4). This undercut matches the function of the channel inasmuch as it enables a pro-

nounced separation of the thread 2 from the thread 1 when the latter drops into the undercut, just as occurs when the thread 2 drops into the channel 12.

The operation is readily understood. When the plating of a heel and toe is begun the backing plate 2 is introduced so as to be combined in the fabric at the knitting points 15, 16 (Figs. 1 and 5) of the needles 17. The leg and instep of the stocking are knitted by a continuous rotation of the needle cylinder, but the heel and toe are knitted by reciprocations of the needle cylinder, that is to say part turns in opposite directions. These reciprocations require constant reversals of the threads 1, 2, so that they first angle off to the left to the knitting point 15 (Fig. 1), then to the right to the knitting point 16 (Fig. 5). As far as known at present it is not possible to plate heels and toes because of the lack of means to separate the yarn on the backward motion (Fig. 5).

It is here that the separator 13 has its advantage. The backing thread 2 will drop into the channel 12 (Fig. 5) and be held apart or away from the face thread 1 by the intervening separator 13. On the other hand, the backing thread 2 drops into the undercut 14 and again becomes adequately separated from the face yarn 1.

In either case a maximum separation or divergence is maintained between threads 1 and 2, not entirely because of the specific shape of the mouthpiece 5 but also because of the horizontal and vertical dispositions of the eyes 9, 10.

The eye 9 will naturally support the outgoing part of the thread 1 in a position higher than the outgoing part of the thread in the eye 10. The yarn carrier 3 therefore serves to maintain a vertical separation of the threads, while the elements 12, 13 and 14 maintain a horizontal separation. Consequently the threads 1 and 2 are always held sufficiently far apart to avoid contact with each other, and so are prevented from twisting. This, in turn, enables the incorporation of plated areas during the process of making fabric with a circular knitting machine.

The position of the separator 13 is not strictly confined to its illustrated position on the mouthpiece 5. A duplicate of it may be employed in lieu of the undercut 14, or the separator may be used at any necessary place on the mouthpiece 5 for the purpose of separating the two different yarns.

Very often the tension of the yarn requires careful regulation. It is where unequally tensioned threads come in contact with each other that twisting is bound to result. By virtue of keeping the face and back threads 1, 2 so decidedly separated, the manner of tension requires little or no consideration. As a matter of practice each thread is controlled

by separate take-ups, and even tension is applied to eliminate the undesired slack.

While the construction and arrangement of the improved plating device for knitting machines is that of a generally preferred form, obviously modifications and changes may be made without departing from the spirit of the invention or the scope of the claims.

10 I claim:—

1. In a knitting machine having a mouthpiece with a passageway directed toward a series of needles in said machine, and a yarn carrier associated with the passageway, said yarn carrier having spaced eyes for independently guiding face and backing threads to the needles; separate means incorporated in the mouthpiece approximately at the lateral extremities of the passageway to alternately receive the backing thread during reciprocatory motion of the needle series and enable the maintenance of a diverging separation thereof from the face thread during said needle series reciprocation.

2. In a knitting machine having a mouthpiece with a passageway directed toward a series of needles said series of needles being capable of both circumrotary and reciprocatory motion, a multiple thread yarn carrier situated in reference to the mouthpiece to assume a confronting relationship to the series of needles, said yarn carrier having spaced eyes for guiding plural threads to the knitting point of the needles; means incorporated in the mouthpiece, substantially at the outlet of the passageway and at each side thereof to receive one of the threads both during circumrotary and reciprocatory motion of the needles to maintain a diverging relationship of each thread to the other.

3. In a knitting machine having a mouthpiece with a passageway directed toward a series of needles, said needles being capable of reciprocatory motions as in knitting heels and toes, and a yarn carrier extending into the mouthpiece; said yarn carrier having a spaced pair of eyes situated in the passageway, the eye nearest the needle series being disposed horizontally and the eye farthest from the needle series being disposed vertically, respectively to guide face and backing threads to the needles, and means on each side of the passageway adjacent to the needles coacting with the vertical eye to alternately catch the backing thread upon every stroke of the needle series in opposite directions during reciprocatory knitting to separate the backing thread from the face thread and maintain a diverging relationship.

4. In a knitting machine having a mouthpiece with a passageway directed toward a series of needles capable of reciprocatory motion as in knitting heels and toes, a yarn carrier extending into the mouthpiece having spaced eyes for guiding face and backing

threads to the needles; an undercut in one side wall of the passageway enabling a recession of the backing thread from the face thread during strokes of the needle series in one direction, and a separator on the mouthpiece adjacent to the other wall of the passageway providing a channel for the recession of the backing thread from the face thread on the reverse strokes of the needle series.

5. The combination of a mouthpiece having a passageway defined by side walls and a bottom, the edge of the bottom at the outlet of the passageway being angled, a separator situated adjacent to one side wall and spaced from the angled edge to define a thread channel, a pronounced undercut in the opposite side wall at the outlet of the passageway also to provide a thread channel, and a yarn carrier having a plural-eyed end extending into the passageway, close to the bottom of the passageway and nearly to said angled edge.

6. A mouthpiece comprising side walls and a bottom defining a passageway, one edge of the bottom being angled and terminating short of one of the side walls, a separator prong extending from said side wall and partly along the angled edge, said separator being spaced from the edge to define a channel adjacent to said side wall, and an undercut in the opposite side wall, opening in said passageway and adjoining said angled edge.
